CONNECTING SWITCH

Elmer O. Swanson, Chicago, Ill., assignor to
 Motorola, Inc., Chicago, Ill., a corporation of
 Illinois

Application September 24, 1951, Serial No. 248,067

1 Claim. (Cl. 200—97)

1

The present invention relates to electric switches and more particularly to improvements in high power coaxial cable switches.

Many radio transmitting systems and all television transmitting systems operate in the relatively high frequency portions of the radio frequency spectrum. Radio frequency currents at these high frequencies have such properties that they may be transmitted or "piped" through coaxial cables or the like. Recent developments in the art have resulted in high power applications of these high frequency currents. Nearly all high frequency transmission systems use coaxial cables at some point in the system to control the direction and application of the high frequency currents and switching devices may be provided to switch the connections between a plurality of the coaxial cables.

When the coaxial cables are conducting high frequency current of relatively high power the construction of coaxial switches for use therewith is complicated by the requirements of adequate insulation. Due to the "skin effect" property of high power high frequency current, only those insulating materials of very high dielectric strength such as ceramics and the like may be used to insulate the coaxial switching contacts or other elements of the switch. However, such insulating materials have poor mechanical strength and are quite fragile. When used in high power applications, the coaxial switch should be operated by remote control, and it has been found that the switch operating mechanism must be carefully controlled in its movement to prevent damage to the relatively fragile insulation materials of the switch.

It is therefore an object of the present invention to provide an improved form of power operated coaxial switch construction for use with high power high frequency current that is dependable in operation and simple in construction.

Another object of the invention is to provide a form of power operated remote controlled coaxial switch having adequate insulation for operation to switch high power high frequency current, the powered switching operation of the switch being controlled in its application to prevent damage to the switch insulation.

A feature of the invention is the provision of a switch housing containing a plurality of switch contacts in spaced axial alignment, and a reciprocating switch operating arm formed of high dielectric insulating material having a conducting sleeve secured thereto for establishing an electrical connection between selected ones of the switch contacts as the arm is reciprocated in axial alignment with the switch contacts.

Another feature of the invention is the provision of electric power means for reciprocating the switch arm of ceramic insulating material

2

together with an associated mechanical dashpot to control the reciprocation of the switch arm and prevent breakage of the arm by sudden power applications.

5 Further objects, features and the attending advantages of the invention will be apparent upon consideration of the following specification and drawings in which:

Fig. 1 is a side elevational view partly broken 10 away showing the power operated high power high frequency coaxial switch;

Fig. 2 is a detailed perspective view of the reciprocal operating arm of the switch;

Fig. 3 is an end view of the switch as seen 15 in Fig. 1;

Fig. 4 is a longitudinal section on the line 4—4 of Fig. 1 showing the arrangement of coaxial cable switching contacts; and

Fig. 5 is a perspective detail of a coaxial cable 20 switch contact.

The power operated high frequency, high power coaxial switch of this invention is comprised of a metallic switch housing preferably formed from a single rectangular bar of metal hollowed out 25 lengthwise to provide space for the coaxial cable switch contacts and a switch operating arm. The switch operating arm is journaled in bearings on the housing to be reciprocated lengthwise through the space of the housing and establish 30 contact between selected ones of the coaxial cable switch contacts. The coaxial cable switch contacts are located in axial alignment at spaced positions along the switch housing. In order to provide adequate insulation the switch arm is 35 formed from a rod of high dielectric material such as a ceramic material, and is provided with a short sleeve of conducting material secured thereto for selectively establishing contact between the various coaxial cable contacts as the 40 switch rod is reciprocated. Electric solenoid driving means are secured to an outer side of the switch housing and their armatures are connected by a connecting member and pivoted lever to the switch arm for reciprocating the same.

45 A dashpot mechanism is also connected to the connecting member to prevent a sudden application of power to the relatively fragile switch arm which might possibly break the arm.

Referring to the drawings, the switch block or 50 housing is shown at 10. The housing 10 is preferably constructed from a single rectangular bar of metal and is bored lengthwise to provide the hollowed out portion 11. Metallic end plates 12 and 13 are fastened to the switch block to form 55 a closed housing. The end plates 12 and 13 are provided with bearing holes 14 and 15 respectively, to receive a reciprocating switch operating arm generally shown at 16.

The switch operating arm 16 is shown in detail 60 in Figs. 2 and 4 of the drawing and includes a cylindrical rod 17 of high dielectric ceramic ma-

terial or the like. One end of the ceramic rod 17 is cemented to a metallic collar 18 which is pivotally connected at 19 to a metallic bearing cylinder 20. The bearing cylinder 20 is journaled in the hole 15 of the end plate 13 and is pivotally connected at 21 to an operating lever 22. The other end of the ceramic rod 17 is cemented to the metal collar 23 pivotally connected at 24 to the metallic bearing cylinder 25 adapted to be journaled in the hole 14 of the 10 end plate 12.

Mounted at spaced lengthwise positions in axial alignment within the hollowed space 11 of the switch block 10 are a plurality of coaxial cable switch contacts 30, 31, and 32 (Fig. 4). 15 Each of the coaxial cable switch contacts are connected to the inner conductor of a coaxial cable whose outer conductor is connected to the metal switch housing 19 through a metal plate such as the metallic plate 33 shown in detail in Fig. 5 of the drawings. Each of the coaxial cable switch contacts, such as the switch contact 30, are provided with a plurality of spring contact fingers such as those shown at 34 and 35 positioned on opposite sides of the switch operating 20 arm 16.

The switch operating arm 16 includes a sleeve 36 of conducting material supported on the ceramic rod 17. The sleeve has an annular opening for receiving the ceramic rod and a square 30 cross section to provide flat surfaces engaged by the fingers of the coaxial cable contacts. The flat surfaces are preferably silver plated and are of a length to form a bridging connection between either coaxial cable contacts 30 and 31, or coaxial 35 cable contacts 31 and 32 as shown in Fig. 4 of the drawings, depending upon the position of the reciprocable switch arm. The contact fingers 34 and 35 of the coaxial cable switch contact 30 are adapted to provide a wiping contact with 40 opposite flat surfaces of the contact sleeve 36 and may also be silver plated to minimize the resistance losses of the high frequency currents to be switched. The contact sleeve 36 may be secured to the ceramic rod 17 by means of cement.

It will be apparent that the reciprocal switch operating arm 16 is relatively fragile, since it includes the ceramic rod 17 with the contact sleeve 36 cemented to the center thereof and the metal collars 18 and 23 cemented to the ends. The power mechanism for reciprocating the switch arm 16 must therefore be controlled in its application to prevent breakage of the switch arm. To this end electric solenoids 40 and 41 are secured to one side of the switch housing 10 and each solenoid is provided with an armature 42 and 43. The armatures 42 and 43 are joined together by a U-shaped connecting bar or arm 44. Also pivotally connected at 45 to the connecting arm 44 is the rod 46 and piston 47 of an air dashpot including the cylinder 48 secured to an extended portion of the end plate 12.

A pair of pedestal plates 50 and 51 are secured to the switch block 10 and one end of the lever arm 22 is pivoted at 53 between the pedestal plates. The connecting bar 44 is pivotally secured at 54 to the lever 22 intermediate its length. The lever arm 22 is pivotally connected at 21 to the bearing cylinder 20 of the switch operating arm 16.

To operate the switch a selected one of the solenoid coils 40 or 41 is energized to move the connecting bar 44, lever arm 22, and switch operating arm 16 in a particular direction. As

will be apparent from Figs. 1 and 4, energization of solenoid 40 causes movement of the arm 16 to the left to connect contacts 30 and 31. Similarly, energization of solenoid 41 will cause movement of the arm 16 to the right to connect contacts 31 and 32. A coaxial cable connected to contact 31 may therefore be selectively connected to cables connected to contacts 30 or 32. The air operated dashpot comprised of the piston 47 and cylinder 48 will prevent the sudden movement which would normally take place when either the solenoid coil 40 or 41 is energized.

The coaxial cable switch as disclosed has been found to be highly satisfactory in actual use. This is to be contrasted with switches which did not include the dashpot and in which the conducting sleeve on the ceramic rod broke loose therefrom as the switch was operated by the solenoids. When the sleeve was secured firmly to the ceramic rod as by a pin, the force of movement caused the ceramic rod to break. The use of the dashpot to control the movement of the arm has obviated these difficulties and provided a commercially successful article.

While the coaxial switch of the present invention has been described particularly in reference to an application for switching the connections between three coaxial cable switch contacts, it will be obvious that the principles of the invention may be applied equally as well to the switch construction for various numbers of coaxial cable contacts, and having various numbers of conducting sleeves on the insulated switch operating arm. Similarly, the position and arrangement of the conducting sleeve on the insulated arm may be modified to suit particular applications. Such changes are within the intended scope and spirit of the invention as defined by the appended claim.

I claim:

In a coaxial switch assembly having an elongated conductive housing forming a longitudinal cavity, a plurality of coaxial cable connectors secured in spaced relation along said housing and each having an outer conductor electrically connected to said housing and an inner conductor extending into the cavity within said housing, conductive end plates enclosing said cavity and having aligned openings therein, and a switch arm journaled in said openings in said end plates including a fragile rod of high dielectric material with a conductive sleeve secured thereto and extending over a portion of the length thereof, said switch arm being capable of reciprocal motion in said cavity for selective engagement of said conductive sleeve with the respective inner conductors of said coaxial cable connectors, the combination of at least one solenoid, a bar actuated by said solenoid for reciprocal motion along an axis parallel to and spaced from the axis of reciprocal motion of the aforesaid switch arm, linkage means for coupling said bar to said switch arm to impart reciprocal motion thereto, and an air operated dash pot mounted coaxially with the axis of reciprocal motion of said bar and having a piston coupled to said bar to prevent sudden movement of said bar by said solenoid.
